UNITED STATES PATENT OFFICE.

GEORGE CASSADY, OF NEW WESTMINSTER, BRITISH COLUMBIA, CANADA, AND
CONRAD FIELD MENDHAM, OF LONDON, ENGLAND.

MECHANISM FOR THE CONVERSION OF RECIPROCATING INTO ROTARY MOTION.

1,132,161.

Specification of Letters Patent.

Patented Mar. 16, 1915.

Application filed October 28, 1912. Serial No. 728,141.

To all whom it may concern:

Be it known that we, GEORGE CASSADY, a subject of the King of Great Britain and Ireland, residing at New Westminster, British Columbia, Canada, and CONRAD FIELD MENDHAM, a subject of the King of Great Britain and Ireland, residing at 85 Gracechurch street, London, E. C., England, have invented certain new and useful Improvements Relating to Mechanism for the Conversion of Reciprocating into Rotary Motion, of which the following is a specification.

This invention relates to mechanism for the conversion of reciprocating into rotary motion.

The invention relates particularly to mechanism such as described in the specification of the prior Patent No. 991699 granted to George Cassady, and has for its object to provide mechanism of simple construction, adapted to withstand the strains imposed upon it and efficiently to transmit motive power, and to provide mechanism capable of adaptation to fluid pressure engines, internal combustion engines, air compressors and pumps, by which a low center of gravity of the motor and transmission mechanism may be secured and a high piston speed, and generally to provide a motor and transmission mechanism operating with economy and efficiency.

According to the invention one member (which when applied to a motor is the driven member of the mechanism) is provided as a rotating body having an open groove or slot, while the other or driving member is provided as a slide carrying a central boss or lug upon which are mounted the contact blocks which run within the open groove or slot in the rotating body, so that thus on the reciprocation of the piston rods of the motor a thrust is imparted in succession to the driven member through the contact blocks whereby it is rotated; while when the mechanism is applied to a pump, the rotation of the rotating member effects the reciprocation in succession of the pump pistons.

The invention is illustrated, by way of example, in the accompanying drawings in its application to a steam engine of the construction described in the specification of

Letters Patent No. 991699 granted to George Cassady.

The drawings show an engine provided with three double-acting cylinders *a* disposed at equal distances around and parallel with the driven shaft *b*.

Figure 1 represents a sectional side elevation of the engine. Fig. 2 represents a transverse sectional view taken on the line A A of Fig. 1, in the direction of the driven member.

In carrying the invention into effect as indicated in the accompanying drawings the driven member *c* is provided as a cylindrical body having an open groove or slot *c*¹ disposed in a plane inclined to its axis advantageously at an angle of 45°. The said groove or slot has its faces flat and disposed in parallel planes. The said body may conveniently be formed of two cylinders, one being of a diameter corresponding to the greater diameter of the body, and the other being of diameter corresponding to the diameter of the body at the bottom of the groove or slot. Each of the cylinders may be bored to fit the driven shaft *b* and may be cut into two parts in a plane corresponding to the plane in which the groove or slot is to be formed. The parts of the smaller cylinder are reversed so that their circular faces lie adjacent one another and the parts of the larger cylinder are separated to receive the smaller cylinder between them.

In mounting the parts of the driven member upon the shaft *b* they are secured against rotation thereon by a feather *d* or key and held together in any suitable manner. As shown in the drawings, a collar *b*¹ may be provided on the shaft *b*, which is made of slightly increased diameter where it is to receive the driven member, and the parts of the driven member are clamped against the collar *b*¹ by means of a nut *e* or nuts screwed upon the end of the portion of the shaft of increased diameter which is threaded for the purpose, and the nut suitably pinned. Alternatively the parts of the driven member may be secured together by means of bolts passing through them. A washer or washers *f* is or are conveniently disposed between the two parts of the smaller cylinder in order that the wear on the faces of the groove or slot *c*¹ may be

taken up. Each of the piston rods *g* at its outer extremity is provided with a head or slide *h* to carry the rotatable contact blocks *i*, which are adapted to be received into the groove or slot *c*¹ and to contact respectively with the side faces thereof. The head or slide *h* of each piston rod *g* is formed to slide in a guide *h*¹ disposed parallel with the shaft *b* and suitably secured to the framing or casing *j* of the engine, and is provided with an inwardly projecting central boss or lug *h*² adapted to carry a spindle *k* to receive the contact blocks *i* which spindle is pinned or otherwise secured in the central boss or lug.

The blocks *i* are formed of cylindrical shape with the one end face disposed at an angle to the axis corresponding to the angle of the open groove or slot, and with the other end face recessed to permit the blocks to be fitted rotatably upon the spindle *k* and to bear upon the side faces of the central boss or lug. Ball bearings may, however, be interposed between the face of each block and the central boss or lug. It is of importance that the distance between the axis of the spindle and the axis of the piston rod should be a minimum.

It will be understood that, in the operation of the engine, on the reciprocation of the piston rods the thrust exerted in succession through the contact blocks serves to effect the rotation of the driven member and of the shaft, the contact blocks meanwhile turning upon their respective spindles and so as continuously to maintain their bearing faces in contact with the side faces of the groove or slot *c*¹. A thrust bearing *l* may be provided adjacent the end of the driven member, and the whole of the transmission mechanism is inclosed within a casing that may thus serve conveniently as an oil bath.

What we claim as our invention and desire to secure by Letters Patent is:—

1. Mechanism for the transmission of motion, or for the conversion of reciprocating into rotary motion, consisting of a rotating body or driven member having an open groove or slot therein, said groove or slot having its faces flat and disposed in parallel planes, and a rectilineally reciprocating member or slide carrying a central boss or lug upon which are mounted the contact blocks which rotate on their axes and run within the open groove or slot in the rotating body or driven member, for operation in the manner for the purposes and substantially as described.

2. Mechanism for the transmission of motion comprising a rectilineally reciprocating member, a head member fixedly mounted on said reciprocating member, said head member being provided with a projecting lug, a spindle mounted in said lug, contact blocks rotatably mounted on said spindle, and a

rotary member having an obliquely-disposed open slot or groove, said groove or slot having its faces flat and disposed in parallel planes, said contact blocks engaging in said slot or groove.

3. Mechanism for the transmission of motion or for the conversion of reciprocating into rotary motion comprising a driving and rectilineally reciprocating member, a head member fixedly mounted on said driving reciprocating member, said head member being provided with a projecting lug, a spindle mounted in said lug, contact blocks rotatably mounted on said spindle, and a rotary driven member having an obliquely disposed open slot or groove, said groove or slot having its faces flat and disposed in parallel planes, said contact blocks engaging in said slot or groove, so as to effect the rotation of the driven member.

4. Mechanism for the transmission of motion comprising a rectilineally reciprocating member, a head member fixedly mounted on said reciprocating member, said head member being provided with a projecting lug, a spindle mounted in said lug, contact blocks rotatably mounted on said spindle, and a rotary member having an obliquely-disposed open slot or groove, said groove or slot having its faces flat and disposed in parallel planes, said contact blocks engaging in said slot or groove, and means for taking up wear on the faces of the open slot or groove of the rotary member.

5. Mechanism for the transmission of motion or for the conversion of reciprocating into rotary motion comprising a driving and rectilineally reciprocating member, a head member fixedly mounted on said driving reciprocating member, said head member being provided with a projecting lug, a spindle mounted in said lug, contact blocks rotatably mounted on said spindle, and a rotary driven member having an obliquely disposed open slot or groove, said slot or groove having its faces flat and disposed in parallel planes, said contact blocks engaging in said slot or groove, so as to effect the rotation of the driven member, and means for taking up wear on the faces of the open slot or groove of the rotary member.

6. Mechanism for the transmission of motion comprising a reciprocating member, a head member fixedly mounted on said reciprocating member, said head member being provided with a projecting lug, a spindle mounted in said lug, contact blocks rotatably mounted on said spindle, and a rotary member having an obliquely-disposed open slot or groove, said contact blocks engaging in said slot or groove, and means for taking up the end thrust of the rotary member.

7. Mechanism for the transmission of motion or for the conversion of reciprocating into rotary motion comprising a driving re-

ciprocating member, a head member fixedly mounted on said driving reciprocating member, said head member being provided with a projecting lug, a spindle mounted in said lug, contact blocks rotatably mounted on said spindle, and a rotary driven member having an obliquely disposed open slot or groove, said contact blocks engaging in said slot or groove, so as to effect the rotation of the driven member, and means for taking up the end thrust of the rotary member.

8. Mechanism for the transmission of motion comprising a reciprocating member, a head member fixedly mounted on said reciprocating member, said head member being provided with a projecting lug, a spindle mounted in said lug, contact blocks rotatably mounted on said spindle, and a rotary member having an obliquely-disposed open slot or groove, said contact blocks engaging in said slot or groove, means for taking up wear on the faces of the open slot or groove of the rotary member and means for taking up the end thrust of the rotary member.

9. Mechanism for the transmission of motion or for the conversion of reciprocating

into rotary motion comprising a driving reciprocating member, a head member fixedly mounted on said driving reciprocating member, said head member being provided with a projecting lug, a spindle mounted in said lug, contact blocks rotatably mounted on said spindle, and a rotary driven member having an obliquely disposed open slot or groove, said contact blocks engaging in said slot or groove, so as to effect the rotation of the driven member, means for taking up wear on the faces of the open slot or groove of the rotary member and means for taking up the end thrust of the rotary member.

In testimony whereof we have respectively hereunto signed our names to this specification in the presence of two subscribing witnesses.
